UNITED STATES PATENT OFFICE.

BALTZAR E. L. DE MARÉ, OF PHILADELPHIA, PENNSYLVANIA.

PROJECTILE FOR ORDNANCE.

SPECIFICATION forming part of Letters Patent No. 660,581, dated October 30, 1900

Application filed April 24, 1898. Serial No. 714,240. (No model.)

To all whom it may concern:

Be it known that I, BALTZAR E. L. DE MARÉ, a subject of the King of Sweden and Norway, residing in Philadelphia, Pennsylvania, have invented certain Improvements in Projectiles for Ordnance, of which the following is a specification.

One object of my invention is to so construct a projectile for ordnance as to combine in one compound shell the penetrating power of an "armor-piercing" shell and the mine power of a "common" explosive shell, a further object being to increase the penetrating power of the armor-piercing portion of the shell. 15 These objects I attain in the manner herein-after set forth, reference being had to the accompanying drawings, in which—

Figure 1 is a longitudinal section of a combined armor-piercing and common shell constructed in accordance with my invention, and Fig. 2 is an end view of the same. Fig. 3 is a sectional view of an ordinary navy percussion or impact fuse used in the base portion of my projectile.

25 The shell shown in Fig. 1 comprises two main parts 1 and 2, the part 1 being the armor-piercing forward section and the part 2 being the explosive section, which is of greater diameter than the armor-piercing section 1 and is intended to fit the bore of the gun, this portion of the shell being preferably provided with the usual rotating band 3.

The armor-piercing forward portion 1 of the shell fits into a recess in the forward end of the portion 2 and is seated at its inner end against an internal shoulder 4, formed in said portion 2 of the shell at the base of said recess, said shoulder 4 constituting the forward termination of a beveled and contracted neck 5 at the forward end of the chamber 6, which is intended to receive the explosive contents of the shell, the rear end of said chamber being closed by a plug 7, which has a central threaded opening 8 for the reception of the fuse or primer 13 of ordinary percussion-base fuse type—such, for example, as that used in the United States Navy—whereby the explosive contents of the shell are fired at the time of impact.

50 In Fig. 3 I have shown one form of an ordinary impact fuse, (a navy percussion fuse,) in which 13 is the hollow body of the fuse,

closed by a screw-plug 15, 14 a brass cylinder with which cylinder is a solid plunger 13 supported by a brittle wire 18, passing through the cylinder 14 and into the side of the plunger, the latter having a firing-nipple 17, adapted to explode a fulminate 16 over a surmounting the perforation leading explosive charge of the shell. Upon impact of the projectile the wire 18 is broken, driving the plunger 19 to be forcibly driven against the bottom of the fuse, causing the nipple 17 to explode the fulminate and flame from which passes through the perforation in the screw-plug 15 to the shell.

The pointed end of the armor-piercing portion 1 of the shell has the usual soft nose 9, and said portion 1 of the shell is retained in its proper position in the portion 2 by means of a plug 10, which closes a chamber 11, formed in said portion 1 of the shell, and which may, if desired, contain explosive material adapted to be fired by means of a suitable time or "delayed-action" primer contained in a central threaded opening 12 of said plug 10. The plug 10 is normally threaded, so as to be screwed into the threaded rear end of the chamber 11, so that the plug 10 has a flange at its rear end externally for adaptation to the bevelled contracted neck 5 of the portion 2 of the shell. Hence when the plug 10 is screwed into the rear end of the portion 1 of the shell it will confine the same firmly to the portion 2, but will permit it to be driven forwardly therefrom when sufficient pressure is exerted to strip that portion of the shell which is in engagement with the neck 5.

When my improved compound shell strikes an armor-plate, the initial momentum of the shell is at first exerted to drive the armor-piercing portion 1 into the plate, an impact being of a diameter of said armor-piercing portion 1 less than that of the bore of the gun, so that the projectile has been discharged. The compound shell will have smaller resistance to overcome than the ordinary full-bore shell. In other words, the shell will penetrate the armor-plate with the momentum of, say, a twelve-inch shell, while its armor-piercing portion will have to overcome resistance to penetrate with, say, an eight-inch shell. As soon as the point of the shell strikes

the explosive in the chamber 6 of the shell is fired, and the energy developed by such explosion effects a double result. In the first place it retards the movement of the non-penetrating portion 2 of the shell and imparts a corresponding forward impulse to the armor-piercing portion 1, thus transferring all or about all of the momentum of the whole shell to the armor-piercing portion thereof, and, secondly, as the pressure due to the explosion still further increases it effects the bursting and scattering of the portion 2 of the shell, so that not only does the improved shell possess the qualities both of an armor-piercing shell acting by penetration with or without subsequent explosion and of a common shell acting by explosion without penetration; but the armor-piercing portion of the shell having less resistance to overcome than an ordinary armor-piercing shell, with approximately the same momentum, will have a greater penetrating power than the ordinary full-caliber shell.

When the chamber 11 of the armor-piercing shell is filled with explosive, said armor-piercing portion may be caused to burst when it has attained its full penetration, thereby still further increasing the destructive effect of the shell.

Having thus described my invention, I claim and desire to secure by Letters Patent—

1. The combination in a projectile for ordnance, of an armor-piercing forward portion and an explosive rear portion detachably connected one to the other, the forward portion serving as a plug for closing the explosive-containing chamber in the rear portion and having a rigid bearing upon the rear portion to prevent movement of said forward portion into the rear portion, and an impact fuse for exploding the charge in the rear portion of the shell whereby the forward or armor-piercing portion will be given an additional impulse upon impact, substantially as specified. 35
2. A combined armor-piercing and explosive projectile consisting of a forward armor-piercing portion and a rear portion containing a chamber for explosive material and having a recess in which said forward portion of the projectile is seated, and a plug carried by said forward portion of the projectile and having a portion engaging with a contracted neck in the rear portion of the same, so as to retain the two portions of the 50 projectile in proper relative position, substantially as specified.

In testimony whereof I have signed my name to this specification in the presence of two subscribing witnesses.

BALTZAR E. L. DE MARE.
